UNITED STATES PATENT OFFICE

LEON C. HICKOK, OF GRAND RAPIDS, MICHIGAN

DENTIST'S BITE-CHECK APPARATUS

Application filed March 12, 1928. Serial No. 230,903.

This invention is an improvement on the apparatus of my Patent No. 1,613,659, issued January 11, 1927, for dental apparatus.

The objects of the invention are,

5 First, to improve the head gear and ear plate structure.

Second, to provide the apparatus with improved adjusting means.

Third, to provide an improved chin rest 10 structure.

Fourth, to provide improved take-up means and gauge for the side straps.

Fifth, to provide improved gauge means for checking the position of the jaws with 15 the nose.

Objects relating to details of construction will appear from the detailed description to follow. The invention is defined in the claims. A structure which is a preferred 20 embodiment of my invention is illustrated in the accompanying drawing, in which:

Fig. 1 is a detail perspective view of my apparatus, the position of the human head and face being indicated in dotted lines with 25 the jaws in open position and the nose gauge thrown down out of use.

Fig. 2 is a similar view with the jaws in closed position and the nose gauge in place.

Fig. 3 is a detail plan of the structure when 30 resting on a table, one take-up structure and case being in section on line 3—3 of Fig. 4.

Fig. 4 is an enlarged detail sectional view on line 4—4 of Figs. 3 and 5, through one of the take-up structures.

Fig. 5 is a detail plan view of the under 35 side of one of the take-up spring cases, the knob being partially broken away showing details of the escapement structure.

The parts of the drawings will be identified 40 by numerals of reference which are the same in all views.

1 is one of the pair of ear plates which are 45 symmetrical duplicates on each side of the head. These ear plates are connected by top head strap 2 pivoted at 21 to the ear plates at each side, and by a bottom head strap 3 secured to the ear plates at pivot 31 at the back of the ear plates. The ear plates are hook-shaped to accommodate the ear. An 50 adjustable take-up strap 4 is pivoted at 41

to each ear plate 1. The pivot 41 is located by the adjustment of the head strap 2 precisely opposite the average pivot point of the mandibular joint. A take-up spring structure puts tension on the strap 4 and a slide 55 42 is adjustable thereon as an indicator. The take-up spring structure comprises a casing 5 having a cover 51. A spring drum 52 is within for winding up the strap 4 and is provided with a spring 53 manipulated by the 60 knob 54. Set screw 55 applies the brake to clamp the same when it is properly set. The spring is held by an escapement structure comprising an escapement wheel 6 and an escapement dog 7 having a projecting handle 65 71 located on the under side of the casing 5.

8 is the chin rest hollowed at 81 to conform to the shape of the average chin. The take-up spring cases pivotally support the chin rest between them by the shouldered screws 70 82 (see Fig. 3). On the chin rest is a forwardly-projecting lug 83 on which is pivoted the nose gauge structure comprising the adjustable arm 9 to which is pivoted the adjustable gauge finger 91 with small knob at 75 the end. This is central of the chin and can be swung to a position under the nose, as indicated in Fig. 2, when the bite check has been properly adjusted.

To use my improved bite check apparatus, 80 it is adjusted on the head of the patient by proper adjustment of the head straps 2 and 3, so that the pivot 41 is located as nearly opposite the pivot point of the mandibular joint as possible. The chin rest is then 85 brought up to the chin and final adjustment is accomplished by manipulation of the escapement dog 7 by the projecting finger 71. The patient works his jaw against the tension and is allowed to come to rest. The 90 slides 42 of the strap 4 yield and eventually when the patient has come to rest are adjusted against the spring case and the spring is locked. The nose gauge is then properly adjusted, and the operator knows substantially 95 the correct position of the jaw for taking the bite. The apparatus can then be set, the guide slides at the side being located, the patient can open his mouth and take a bite, and the instrument will exactly check the correct 100

position of the jaws, thereby securing the correct imprint of the same.

Of course the apparatus will operate fairly well without the nose gauge, but it is advantageous to have it. The apparatus might be operated without the swivels on the chin rest but much more perfect work is accomplished with those means. Relative adjustment secured by manipulation of the escapement dogs is highly desirable in securing most perfect and even adjustment of the instrument, but of course the escapement can be omitted, losing this advantage.

I desire to claim the invention specifically as illustrated as well as broadly and also generally as to its separate features, as pointed out in the appended claims.

Having thus described my invention, what I claim as new and desire to secure by Letters Patent is:

1. In a dentist's bite check apparatus, the combination of a head gear comprising adjustable top and back head straps, hook-shaped ear plates with a pivot capable of adjustment to positions opposite the mandibular joint, straps and spring take-up devices at each side connected at the pivots to said ear plates, a chin rest with swivel connections to the said take-up devices at each side, sliding gauge devices on the take-up straps, a screw to set the take-up spring devices, escapement dogs to adjust the tension of the spring and regulate the take-up device, and a nose gauge comprising pivoted arms pivoted centrally to the chin rest and adjustable frictionally to proper relation with the nose, all coacting as described.

2. In a dentist's bite check apparatus, the combination of a head gear comprising adjustable top and back head straps, hook-shaped ear plates with a pivot capable of adjustment to positions opposite the mandibular joint, straps and spring take-up devices at each side connected at the pivots to said ear plates, a chin rest with connections to the said take-up devices at each side, sliding gauge devices on the take-up straps, a screw to set the take-up spring devices, and escapement dogs to adjust the tension of the spring and regulate the take-up, coacting as specified.

3. In a dentist's bite check apparatus, the combination of a head gear comprising adjustable top and back head straps, hook-shaped ear plates with a pivot capable of adjustment to positions opposite the mandibular joint, straps and spring take-up devices at each side connected at the pivots to said ear plates, a chin rest with connections to the said take-up devices at each side, sliding gauge devices on the take-up straps, and a screw to set the take-up spring devices, coacting as described.

4. In a dentist's bite check apparatus, the combination of a head gear comprising ad-

justable top and back head straps, hook-shaped ear plates with a pivot capable of adjustment to positions opposite the mandibular joint, straps and spring take-up devices at each side connected at the pivots to said ear plates, a chin rest with connections to the said take-up devices at each side, and a screw to set the take-up spring devices, as specified.

5. In a dentist's bite check apparatus, the combination of head gear and side straps and spring take-up devices, a chin rest with connections at each side to the take-up devices, and a nose gauge comprising pivoted arms pivoted centrally to the chin rest and adjustable frictionally to proper relation with the nose, as specified.

6. In a dentist's bite check apparatus, the combination of a head gear comprising adjustable top and back head straps, hook-shaped ear plates with a pivot capable of adjustment to positions opposite the mandibular joint, straps and spring take-up devices at each side connected at the pivots to said ear plates, a chin rest with connection to the said take-up devices at each side, and means to set the take-up spring devices, as specified.

In witness whereof I have hereunto set my hand.

LEON C. HICKOK.
